PACKAGING CONTAINER FOR LIQUIDS OR THE LIKE

John R. Anderson and William P. Jacobson, Rockford,
Ill., assignors to Anderson Bros. Mfg. Co., Rockford,
Ill.

Filed June 18, 1971, Ser. No. 154,714

Term of patent 14 years

Int. Cl. D9—03

U.S. Cl. D9—219

FIG. 1 is a front elevational view of a packaging container for liquids or the like showing our new design, the left side elevational view being a mirror image thereof;

FIG. 2 is a top view of the packaging container for liquids or the like;

FIG. 3 is a right side elevational view of the packaging container for liquids or the like, the rear side being identical thereto;

FIG. 4 is a bottom view of the packaging container for liquids or the like;

FIG. 5 is a sectional view taken along line 5—5 of FIG. 4; and

FIG. 6 is an enlarged fragmentary sectional view taken on line 6—6 of FIG. 5.

We claim:

The ornamental design for a packaging container for liquids or the like, substantially as shown and described.
